LAMP SOCKET

Henry N. Fairbanks, Rochester, N. Y., assignor to
 Eastman Kodak Company, Rochester, N. Y., a
 corporation of New Jersey

Application June 22, 1942, Serial No. 447,987

8 Claims. (Cl. 88—24)

The present invention relates to lamp sockets of the type wherein a lamp is adapted to be inserted thereinto by a straight thrust as distinguished from screw sockets, and particularly to the combination of such a socket with a picture projecting apparatus.

As is well known, it is common practice to provide sockets for electric lamps into which the lamp is inserted by a straight thrust and then given a partial turn to lock it in place therein. These sockets are commonly referred to as bayonet type sockets and are adapted to receive lamps having a complementary bayonet type base. Sockets of this type include a resilient contact in the center of the base thereof adapted to engage the central contact in the base of the lamp, and the resiliency of this contact in the socket opposes the insertion of the lamp into the socket. This contact in the socket is made resilient for two reasons. First, it forms an important part of the bayonet type lock in that it acts to hold the parts in locking relationship after the lamp has been partially rotated to establish the relationship. Secondly, it insures a good electrical contact between the socket contact and the contact in the base of the lamp.

When lamp sockets of this type are used on apparatus which is subject to vibration and jars it has been found imperative to place a strong spring behind the contact in the lamp socket in order to prevent the lamp from jarring from a locked relationship in the socket, to hold the lamp against any vibration, and to insure a good contact between the socket contact and the lamp contact at all times. The strength of the spring necessary behind the base contact of a socket of the type set forth will vary with the particular application of the socket.

In order to insert a lamp into a socket of the type in question it is necessary to thrust the same into the socket against the opposition of the spring contact by grasping the glass globe of the same. In cases where strong springs have been required in sockets it has been found that the force required to place the lamp in the socket has been sufficient to break the glass globe of the lamp. As a result, a lamp which might be expensive is wasted and there is a very good chance that the person's hand is cut in the operation. Even if the thrust required in inserting a lamp into such a socket is not in fact sufficient to break the lamp globe, it is often sufficient to make a person wary of changing a lamp in the socket for fear it will break. In addition, when one is compelled to firmly grip a

hot lamp, probably burned out, in order to remove it from its socket he is liable to get a painful burn. It is also significant that lamp sockets of the type in question are very often mounted in rather inaccessible places so that in order to insert a lamp therein the lamp globe must be gripped at the extreme end by the tips of the fingers only with the result that the thrust necessary to insert the lamp into the socket must be transmitted throughout the entire length of the lamp globe.

Therefore, the primary object of the present invention is the provision of a lamp socket into which a lamp is adapted to be inserted by a straight thrust in opposition to a resilient contact in the base of the socket after which it is adapted to be locked in said socket by the engagement of cooperating parts on the lamp base and socket shell and means for purposely decreasing the resilient force of said contact prior to changing a lamp in the socket and again increasing the resilient force of said contact after the lamp is changed and is ready for use.

Another object is the provision of a socket of the type set forth which is movable between two positions, a lamp changing position and a projecting position, and including means for automatically decreasing and increasing the resilient force of the socket contact as the socket is moved to and from said lamp changing position, respectively.

A further object is the provision of a socket of the type set forth wherein the circuit to the socket is automatically broken when the same is moved to said lamp changing position and automatically completed when returned to the projection position so that a person changing a lamp is not startled by lighting up of a lamp during its insertion into the socket.

And yet another object of the present invention is the provision of a socket of the type set forth which includes a contact having sufficient resiliency to initially locate a lamp in the socket and permit easy insertion of the lamp thereinto, and the resiliency of which contact is augmented by the resiliency of a second contact when the socket is moved to its projecting position.

Another object is to have the socket mounted on a lamp house door of a picture projector so that opening and closing of the door moves the socket between its lamp changing and projecting positions, respectively.

The novel features that I consider characteristic of my invention are set forth with particu-

larity in the appended claims. The invention itself, however, both as to its organization and its methods of operation, together with additional objects and advantages thereof, will best be understood from the following description of specific embodiments when read in connection with the accompanying drawing in which,

Fig. 1 is a side elevational view, on reduced scale, of a well known type motion picture apparatus in combination with the lamp house of 10 which the socket constituting the present invention has been shown for the purpose of illustrating one application of the same.

Fig. 2 is an enlarged partial sectional view of the lamp house of the projector shown in Fig. 1, 15 showing how a socket constructed in accordance with one embodiment of the present invention might be mounted on the lamp house door, and showing the lamp house door closed,

Fig. 3 is a view similar to Fig. 2 but showing 20 the lamp house door opened and the socket moved therewith to a lamp changing position,

Fig. 4 is a plan view of the lamp socket with the lamp removed and showing the manner of mounting it on the lamp house door, and 25

Fig. 5 is a top plan view of the live resilient contact mounted on the base of the lamp house.

Like reference characters refer to corresponding parts throughout the drawing.

Generally, the present invention comprises a lamp socket into which a lamp is adapted to be inserted by a straight thrust against the opposition of a resilient contact after which it is locked in said socket by the combined cooperation of engaging parts on the socket shell and lamp base and the resilient force of the contact. The structure is such that the resilient force of the contact may be purposely reduced to a minimum to facilitate changing a lamp on the socket and may thereafter be purposely increased to firmly hold the lamp in the socket during projection. The structure is so arranged that when the resilient force of the socket contact is reduced the circuit to the socket is automatically broken, and when the resilient force is again increased the circuit to the socket is again completed.

For purposes of disclosing the operation and advantages of a socket constructed in accordance with the present invention I have chosen to show the same in combination with a well known type of motion picture apparatus. However, it will be readily appreciated by one skilled in the art that the socket of the present invention is not limited to the specific application set forth but is readily adapted for use on a number of different apparatus.

Referring now to the drawing, the motion picture projector shown in Fig. 1 is one of a well known type in which a motion picture film, not shown, is adapted to be fed, by a film feeding mechanism in a known manner, thru a film gate 18 located at the front wall of a lamp house 11. The lamp house encloses a projection lamp the rays of which pass through the film as it passes the film gate and to and through a projection lens 12 to a suitable screen. As shown, one side wall of the lamp house 11 is pivoted to the bottom of the lamp house, as shown at 13, Figs. 2 and 3 to form a door 14 which can be opened to provide access to the interior of the lamp house. The door 14 may be locked in a closed position by any suitable type of latch indicated at 15 in Fig. 1.

In accordance with the present invention the

socket for the projection lamp 16 is one of the bayonet type and into which the lamp is adapted to be inserted by a straight thrust and after which the lamp is given a partial turn to lock the same in the socket. As shown, the lamp socket may comprise a cylinder 17 of any suitable insulating material, such as porcelain, hard rubber, etc., having a circular recess 18 into which the base of a lamp is adapted to be inserted. The circular recess 18 is lined with a metal shell 19 the upper ends of which are formed in the shape of a U as indicated at 20 to form a part of a bayonet lock. Looking at Fig. 4 it will be noticed that the inturned edge of the shell 19 is provided with two diametrically opposed arcuate slots 21. These slots are complementary in shape to two diametrically opposed wings 22 on the lamp base 23 so that when the wings on the lamp base are lined up with the arcuate slots the lamp base may be inserted into the socket after which a partial turn of the lamp relative to the socket will prevent the lamp from being pulled from the socket.

Slidably extending through a bore 25 in the bottom of the socket is a contact 26 including a cap 27 located in the socket recess and a stem 28 extending beyond the base of the socket and being slidably guided by a sleeve bearing 29 fixed in the base of the socket. The contact 26 is normally forced into the socket recess by a coiled spring 30 encircling the stem 28 of the contact and being held under compression between the cap of the plunger and a fixed part of the socket, as clearly shown in Figs. 2 and 3.

It will be readily appreciated that when a lamp is inserted into the socket the center contact 31 in the base thereof contacts the cap 27 of the contact 26 and that the spring 30 opposes its insertion into the socket. This spring, however, is comparatively light, being of only sufficient strength to initially hold the lamp in locking relation with the socket, and does not offer the opposition to the insertion of the lamp which known resilient contacts do which are relied upon to exert the full force required to finally position a lamp in its socket under operating conditions. A stop pin 32 extending radially through the end of the stem 28 prevents the contact 26 from being propelled from the socket by the spring 30 when a lamp is removed from the socket.

The socket may be attached to the inside of the lamp house door 14 in any manner to move between two positions when the door is opened and closed. To facilitate a final focusing of the lamp relative to the picture strip moving through the film gate I have shown the socket fixed to a supporting bracket 33 including spaced ears 34 pivoted to lugs 35 on the lamp house door. A screw 36 fixed to the lamp house door extends through a hole in an upstanding arm 37 on the bracket and by means of an adjusting nut 38 on the screw the bracket and socket can be tilted relative to the lamp house door and consequently the projection aperture across which the film passes. Gravity may be relied upon to hold the upstanding arm 37 of the bracket against the adjusting nut 38 or a spring, not shown, may be mounted at the pivot point of said bracket to normally pivot it in a clockwise direction, looking at Figs. 2 and 3.

Mounted on the bottom wall 40 of the lamp house is a second contact 41. As shown, this contact may constitute a strip of resilient metal attached at one end to posts 42 on the bottom of the lamp house by screws 43. A second coil spring

44, mounted on a locating stud 45 in the bottom wall of the lamp house, is held under compression between the underside of the free end of said contact 41 and a shoulder on said stud. Looking at Fig. 3, when the lamp house door is opened to change a lamp in the socket the only spring tending to force the contact 26 into the socket, and thereby opposing the insertion of a lamp into the socket, is the comparatively light spring 30 which is not strong enough to firmly hold the lamp in the socket under operating condition, but which is strong enough to initially position the lamp in the socket, or strong enough to primarily hold the lamp and socket in locking relation.

When the door of the lamp house is closed and the lamp is ready for use under ordinary operating conditions, the end of the stem 28 of contact 26 engages the free end of contact 41 and causes a retraction, or compression, of the spring 44. Thus, the force of the spring 44 augments that of the spring 30 and the lamp is firmly held on locking relationship and a good electrical contact between cap 27 of contact 26 and the contact in the base of the lamp is insured.

It will be observed that the metal shell 19 of the socket is adapted to be electrically to one side of a source of potential through a binding post 46 in contact therewith and a wire 47 connected to said binding post. The contact 26 is insulated from the metal socket shell by circular shoulder 48 of insulating material forming a part of the socket, and in fact is dead whenever the lamp house door is open. The other side of the source of potential is connected to the contact 41 by a wire 49 and when the lamp house door is closed and the end of the stem 28 is brought into engagement with the contact 41 the circuit of the lamp socket is completed. Consequently, the contacts 26 and 41 in effect constitute a switch for the circuit to the socket, and which switch is automatically opened and closed when the lamp house door is opened and closed, respectively; or stating it more broadly, a switch which is automatically opened and closed when the lamp socket is moved to and from its lamp changing position, respectively. It will thus be apparent that when a lamp is inserted into the socket the same will not light and startle the person performing the operation because the circuit to the socket is automatically broken when the socket is moved to its lamp changing position.

It is pointed out that the present invention is not limited to use with sockets and lamps having bayonet type locking connections, but is useful and adapted for use with any socket into which a lamp is adapted to be inserted by a straight thrust against the opposition of resilient contact the resilient force of which forms a part of, or effects the operation of a locking mechanism for locking the lamp in the socket after once being inserted thereunto by a straight thrust. A socket and lamp combination which would meet these requirements, but which does not include a bayonet type locking arrangement, is disclosed in pending U. S. patent application Serial No. 371-242, filed Dec. 23, 1940, in the name of Joseph Mihalyi. In this socket and lamp combination referred to, a screw base lamp is adapted to be inserted into a socket by a straight thrust and in opposition to the resilience of a contact in the base of the socket. The lamp is locked in the socket when one end of a bellcrank pivoted in the side of the socket engages a thread on the lamp base and the engagement of the two being

dependent upon the resilient force of the contact tending to push the lamp from the socket.

It is believed that the novel features and advantages of the present socket construction will be readily apparent from the above description thereof. By way of summation, it will suffice to say that the present socket construction provides the necessary strong spring in the socket for holding the lamp firmly against movement due to vibrations or jars, and at the same time permits the force of the spring to be purposely released to facilitate the insertion of a lamp into the socket. The added feature of automatically breaking the circuit to the socket when the resilient force of the socket contact is decreased to permit an easy insertion of a lamp into the socket and automatically closing the circuit when the resilient force of the contact is again increased after insertion of the lamp presents advantages which will be readily apparent to one skilled in the art. While the disclosed socket arrangement is particularly adapted for use with motion picture apparatus as set forth it will be readily apparent that the basic features of the same would be useful in other applications and could be readily applied to other apparatus.

Although I have shown and described certain specific embodiments of my invention, I am fully aware that many modifications thereof are possible. My invention, therefore, is not to be limited to the precise details of construction shown and described but is intended to cover all modifications coming within the scope of the appended claims.

Having thus described my invention, what I claim is new and desire to secure by Letters Patent of the United States is:

1. In an apparatus of the type described the combination of a lamp socket into which a lamp is adapted to be inserted by a straight thrust, means for locking a lamp in said socket after being thrust thereinto, said means including a member in said socket adapted to engage a projecting portion on the base of the lamp after the same is fully inserted into the socket, a movable contact in the bottom of the socket against which the lamp base is adapted to abut, resilient means normally forcing said contact into said socket and thereby to oppose insertion of a lamp into said socket and to oppose the removal of the cooperating parts of said socket and lamp base from locking relationship when once established, and means for alternately decreasing and increasing the strength of said resilient means to facilitate changing a lamp in said socket and to firmly lock the lamp in the socket after such a change, respectively.

2. In an apparatus of the type described the combination of a lamp socket into which a lamp is adapted to be inserted by a straight thrust, means for locking a lamp in said socket after being thrust thereinto, said means including a member in said socket adapted to engage a projecting portion on the base of the lamp after the same is fully inserted into the socket, a movable contact in the bottom of the socket against which the lamp base is adapted to abut, a plurality of resilient means adapted to normally force said contact into the socket and thereby oppose insertion of a lamp into said socket and to oppose the removal of the cooperating parts of said socket and lamp base from locking relationship when once established, and means for purposely rendering certain of said resilient means in-

effective to facilitate changing a lamp in said socket and for again rendering the same effective after such a change to firmly lock the lamp in the socket.

3. In an apparatus of the type described the combination of a lamp socket into which a lamp is adapted to be inserted by a straight thrust, means for locking a lamp in said socket after being thrust thereinto, said means including a member in said socket adapted to engage a projecting portion on the base of the lamp after the same has been fully inserted into the socket, a resilient contact in the base of said socket adapted to oppose insertion of a lamp into said socket and to oppose the removal of the cooperating parts of said socket and lamp base from locking relationship when once established, said contact including an end extending through the base of said socket, means for movably mounting said socket to move from a lamp changing position to a projecting position, a second resilient contact located to be engaged and retracted by the extending end of said contact when the socket is moved to its projecting position whereby it augments the resiliency of said first contact to firmly lock the lamp in the socket, and to be disengaged by said contact when the socket is moved to its lamp changing position whereby only the resiliency of the contact alone need be overcome in effecting a change of lamp.

4. In an apparatus of the type described the combination of a lamp socket into which a lamp is adapted to be inserted by a straight thrust, means for locking a lamp in said socket after being thrust thereinto, said means including a member in said socket adapted to engage a projecting portion on the base of the lamp after the same has been fully inserted into the socket, a resilient contact in the base of said socket adapted to oppose insertion of a lamp into said socket and to oppose the removal of the cooperating parts of said socket and lamp base from locking relationship when once established, said contact including an end extending through the base of said socket, means for movably mounting said socket to move from a lamp changing position to a projecting position, a second resilient contact located to be engaged and retracted by the extending end of said first contact when the socket is moved to its projecting position, whereby it augments the resiliency of said first contact to firmly lock the lamp in the socket, and to be disengaged by said contact when the socket is moved to its lamp changing position whereby only the resiliency of the contact alone need be overcome in effecting a change of lamp, and means for automatically interrupting the circuit to said socket when the same is moved to its lamp changing position, and for automatically completing said circuit when the socket is moved to its projecting position.

5. In a picture projector the combination with a lamp house, a pivoted door on said lamp house for opening and closing the same, a bayonet type lamp socket mounted on said door to move therewith and adapted to receive a lamp having a complementary bayonet type base, a resilient contact in the base of said socket adapted to engage the base of the lamp and including an end extending through the base of the socket, a second resilient contact mounted on a fixed part of said lamp house in a position to be engaged and retracted by the extending end of said first contact when the door is closed, whereby the resiliency force of the second contact augments the

force of the first to firmly hold the lamp in locked relation in the socket, and adapted to be disengaged by said first contact when the door is open, whereby only the resilient force of the first contact need be overcome in the operation of changing a lamp in the socket.

6. In a picture projector the combination with a lamp house, a pivoted door on said lamp house for opening and closing the same, a bayonet type lamp socket mounted on said door to move therewith and adapted to receive a lamp having a complementary bayonet type base, a resilient contact in the base of said socket adapted to engage the base of the lamp and including an end extending through the base of the socket, a second resilient contact mounted on a fixed part of said lamp house in a position to be engaged and retracted by the extending end of said first contact when the door is closed, whereby the resilient force of the second contact augments the force of the first to firmly hold the lamp in locked relation in the socket, and adapted to be disengaged by said first contact when the door is open, whereby only the resilient force of the first contact need be overcome in the operation of changing a lamp in the socket, and means for automatically breaking and completing the circuit to said socket when the lamp house door is opened and closed, respectively.

7. In a picture projector the combination with a lamp house, a pivoted door on said lamp house for opening and closing the same, a bayonet type lamp socket mounted on said door to move therewith and adapted to receive a lamp having a complementary bayonet type base, means for electrically connecting the shell of said socket to one side of a source of potential, a resilient contact in the base of said socket adapted to engage the contact in the lamp base, said contact being normally insulated from the source of potential and including an end extending through the base of the socket, a second resilient contact mounted on a fixed part of said lamp house in a position to be engaged and retracted by the extending end of said first contact when the door is closed, whereby the resilient force of the second contact augments the force of the first to firmly hold the lamp in locked relation in the socket, and adapted to be disengaged by said first contact when the door is open, whereby only the resilient force of the first contact need be overcome in the operation of changing a lamp in the socket, said second contact being connected to the other side of the source of potential whereby said two contacts constitute a switch for the circuit to the lamp socket.

8. In a picture projector the combination with a lamp house, a pivoted door on said lamp house for opening and closing the same, a bayonet type lamp socket mounted on said door to move therewith and adapted to receive a lamp having a complementary bayonet type base, means for electrically connecting the shell of said socket to one side of a source of potential, a plunger contact extending through the bottom of said socket and adapted to move into and out of said socket, said plunger contact including a head within the socket adapted to engage the center contact in the base of a lamp inserted into said socket and an end extending below the bottom of said socket, a compression spring situated between the head of said plunger contact and the base of the socket and normally forcing said contact into said socket, a second resilient contact mounted on a fixed part of said lamp house in

a position to be engaged and retracted by the extending end of said plunger contact when the door is closed, whereby the resilient force of said second contact augments the force of said compression spring to firmly hold the lamp in locked relation in the socket, and adapted to be disengaged by said first contact when the door is opened, whereby only the force of said compres-

sion spring need be overcome in the operation of changing a lamp in the socket, said plunger contact normally insulated from the source of potential, and said second contact connected to the other side of said source of potential whereby said two contacts constitute a switch for the circuit to the lamp socket.

HENRY N. FAIRBANKS.
